(57) **CLAIM**

The ornamental design for a weightlifting bar as shown and described.

DESCRIPTION

FIG. 1 is a top, front, left perspective view of a weightlifting bar showing our new design;

FIG. 2 is a bottom, rear, right perspective view thereof;

FIG. 3 is a front view thereof;

FIG. 4 is a rear view thereof;

FIG. 5 is a right side view thereof;

FIG. 6 is a left side view thereof;

FIG. 7 is top view thereof; and,

FIG. 8 is a bottom view thereof.

The even-length broken lines immediately adjacent to the shaded area define the bounds of the claimed design and form no part thereof. The even-length broken lines depicting the remainder of the weightlifting bar form no part of the claimed design.

1 Claim, 8 Drawing Sheets
